UNITED STATES PATENT OFFICE.

THOMAS LLOYD, OF PATERSON, NEW JERSEY.

SAFE FOR FIRE-WORKS.

SPECIFICATION forming part of Letters Patent No. 372,811, dated November 8, 1887.

Application filed August 2, 1887. Serial No. 245,924. (No model.)

To all whom it may concern:

Be it known that I, THOMAS LLOYD, of Paterson, in the county of Passaic and State of New Jersey, have invented certain new and useful Improvements in Safes for Fire-Works, of which the following is a specification.

This invention relates to an improved safe for storing fire-works in a secure and reliable manner, so that in case of explosion no damage by fire or otherwise will be done to the building in which the safe is located; and the invention consists of a safe for fire-works made of boiler-iron or other suitable material and connected by a ventilating-pipe to the chimney or roof of the building, said safe and pipe being covered by asbestos cloth or other suitable non-combustible material.

In the accompanying drawings, Figure 1 represents a front elevation, and Fig. 2 a vertical transverse section, of my improved safe for fire-works.

Similar letters of reference indicate corresponding parts.

Referring to the drawings, A represents a safe for fire-works and similar goods, which is made of boiler-iron or other suitable material and of any suitable size. To an opening, a, in the top part of the safe is connected a ventilating-pipe, B, which is conducted either to a chimney or directly to the roof. The safe A

and ventilating-pipe B are covered by a layer, C, of asbestos cloth or other suitable non-combustible covering.

In case of the explosion of the fire-works stored in the safe the smoke and flame can escape through the ventilating-pipe B without causing any damage to the surrounding part of the building, or without causing the bursting of the safe, which would be the case in a closed safe without escape-pipe.

The ventilating-pipe acts as a safety device for the safe, and prevents all danger arising from explosion of the fire-works stored in the safe.

Having thus described my invention, I claim as new and desire to secure by Letters Patent—

A safe for fire-works, made of boiler-iron or other suitable material and provided with a ventilating-pipe extending to the chimney or roof, said safe and pipe being covered by a layer of non-combustible material, substantially as set forth.

In testimony that I claim the foregoing as my invention I have signed my name in presence of two subscribing witnesses.

THOMAS LLOYD.
